(57) **CLAIM**

The ornamental design for a fan with outflow baffle, as shown and described.

DESCRIPTION

FIG. 1 is a perspective view of an outlet side of a fan with an outflow baffle of a first embodiment of the invention, with pivotable flaps in an open orientation;

FIG. 2 is an axial view of an intake side of the fan/baffle combination of FIG. 1, showing a hub and a plurality of curved blades extending therefrom;

FIG. 3 is an axial view of the outlet side of the fan/baffle combination of FIG. 1, with the flaps shown edge-on;

FIG. 4 is a side view of the fan/baffle combination, taken looking from the right of FIG. 3;

FIG. 5 is a side view of the fan/baffle combination, taken looking from the left of FIG. 3;

FIG. 6 is a side view of the fan/baffle combination, taken looking from the top of FIG. 3; and

FIG. 7 is a side view of the fan/baffle combination, taken looking from the bottom of FIG. 3;

FIG. 8 is a perspective view of an outflow baffle;

FIG. 9 is an axial view of an outlet side of the baffle of FIG. 8;

FIG. 10 is an axial view of an inlet side of the baffle of FIG. 8;

FIG. 11 is a side view of the baffle, taken looking from the right side of FIG. 9;

FIG. 12 is a side view of the baffle, taken looking from the left side of FIG. 9;

FIG. 13 is a side view of the baffle, taken looking from the top of FIG. 9; and,

FIG. 14 is a side view of the baffle, taken looking from the bottom of FIG. 9.
